Primary Examiner — Charles D Hanson

(57) **CLAIM**

The ornamental design for the bone fixation implant, as shown and described.

DESCRIPTION

FIG. 1 is a front, top perspective view of the bone fixation implant comprising the new design;

FIG. 2 is a rear, bottom perspective view of the design of FIG. 1;

FIG. 3 is a top view of the design of FIG. 1;

FIG. 4 is a bottom view of the design of FIG. 1;

FIG. 5 is a right side elevational view of the design of FIG. 1, where the left side elevational view is a mirror image thereof;

FIG. 6 is a rear elevational view of the design of FIG. 1; and

FIG. 7 is a front elevational view of the design of FIG. 1.

FIG. 8 is a top, front perspective view of an alternative embodiment of the bone fixation implant of FIG. 1;

FIG. 9 is a bottom, rear perspective of the design of FIG. 8;

FIG. 10 is a top view of the design of FIG. 8;

FIG. 11 is a bottom view of the design of FIG. 8;

FIG. 12 is a right elevational view of the design of FIG. 8, wherein the left elevational view is a mirror image thereof;

FIG. 13 is a rear elevational view of the design of FIG. 8; and

FIG. 14 is a front elevational view of the design of FIG. 8.

FIG. 15 is a top, front perspective view of an alternative embodiment of the bone fixation implant of FIG. 1;

FIG. 16 is a bottom, rear perspective of the design of FIG. 15;

FIG. 17 is a top view bottom view of the design of FIG. 15;

FIG. 18 is a bottom view of the design of FIG. 15;

FIG. 19 is a right elevational view of the design of FIG. 15, wherein the left elevational view is a mirror image thereof;

FIG. 20 is a rear elevational of the design of FIG. 15; and

FIG. 21 is a front elevational view of the design of FIG. 15.

FIG. 22 is a top, front perspective view of an alternative embodiment of the bone fixation implant of FIG. 1;

FIG. 23 is a bottom, rear perspective of the design of FIG. 22;

FIG. 24 is a top view bottom view of the design of FIG. 22;

(Continued)

FIG. 25 is a bottom view of the design of FIG. 22; FIG. 26 is a right elevational view of the design of FIG. 22, wherein the left elevational view is a mirror image thereof; FIG. 27 is a rear elevational of the design of FIG. 22; and, FIG. 28 is a front elevational view of the design of FIG. 22. The broken lines in the figures are directed to the environment and are for illustrative purposes only; the broken lines form no part of the claimed design.
